UNITED STATES PATENT OFFICE.

THOMAS HENRY McFERREN, OF MECCA, INDIANA, ASSIGNOR TO CHICAGO FIRE BRICK CO., OF CHICAGO, ILLINOIS.

MOLD.

1,160,299.

Specification of Letters Patent. Patented Nov. 16, 1915.

Application filed March 13, 1913. Serial No. 753,913.

To all whom it may concern:

Be it known that I, THOMAS HENRY McFERREN, a citizen of the United States, residing at Mecca, in the county of Parke and State of Indiana, have invented a certain new and useful Improvement in Molds, of which the following is a full, clear, concise, and exact description, reference being had to the accompanying drawings, forming a part of this specification.

My invention relates to dies for making coping, and has for its object the provision of such a die which can be used to form three pieces of single slant coping with one operation, the three pieces, of course, being fastened together as they are formed in the die, but arranged in such a manner that incisions are provided at the time of forming, at which incisions the three-piece product may be very easily separated to resolve it into its three individual pieces of single slant coping. With the coping thus formed of three unit sections in the process of making I have a structure which can be very readily placed in the kiln to be fired with little attention, and this is a great advantage as the two piece coping sections when placed in the kiln have to be placed very close together to prevent them from falling and in this way the kiln draft is shut off to such an extent that the coping will not be well glazed.

I am further enabled by the use of my improved die to provide a knife cutting mechanism to separate the finished piece and thus avoid the difficulty hitherto present in the manufacture of two or four piece copings in which it is necessary to use a wire stretched over a bow to separate the finished section from that remaining in the die, thus causing from one and one-half to two inches of clay to remain in the die which has to be pulled out by the hands of the operators, occasioning thereby several minutes' delay after making each section of coping.

I also find that coping made from four piece dies has not enough slope to it to make a good marketable article. Further in making the two piece sections the bell is attached to the die by bridges which very frequently bend so as to disarrange the position of the bell, thus causing the coping either to break or warp in drying due to the difference in the thickness of the clay.

This warping is always in one direction and

as the coping will not reverse when setting in the kiln to burn, thus the article is unsatisfactory.

By means of a specially constructed die I am enabled to construct single slant coping in three piece sections, thus to avoid the flaws of the two and four piece sections, and I will explain one form of die which I utilize in forming these sections through the aid of the accompanying drawings illustrating the same in which—

Figure 1 is a sectional view of a die constructed in accordance with my invention; Fig. 2 is a top view of a fixed three piece section of coping; Fig. 3 is a sectional view on line *a—a* of Fig. 1; Fig. 4 is a perspective view of a single slant coping unit, and Fig. 5 is a bottom view of the former plate.

Referring more particularly to Fig. 1, I show a bell 1 forming part of a die and which is placed interiorly of the die element 2. The element 2 is securely bolted to the mud cylinder of a steam clay press in any manner desired and the bell 1 is suitably held upon a rod 3, which rod bears 80 against the bell through the interposition of the washer 4. The washer 4 has a very large surface and being interposed between the rod 3 and the bell 1 securely holds the bell in place and prevents its shifting to any objectionable extent. A suitable nut 5 holds these parts together to any suitable rigid structure, not shown. A shaft 6 extends through the center of the bell and carries a knife 7 arranged upon a knuckle joint 8 so that turning the shaft 6 in a clockwise direction will tend to throw the knife 7 outwardly after the former plate 9 has been moved from the position it occupies in Fig. 1, thus to permit cutting off the protruding 95 extremity of the material issuing forth out of the orifice 10 provided between the bell 1 and the element 2. As the shaft 6 is turned in a contra-clockwise direction by reason of the knuckle joint 8, the knife is withdrawn into the position shown in Fig. 1. A dowel pin 11 is interposed between the elements 3 and 4 to hold them together and to prevent the bell 1 from turning. The former plate 9 is adapted to move downwardly in the path of the arrow as indicated in dotted lines at 12 as the material is being forced out through the orifice 10. Initially the former plate 9 is held in position within element 2 by a three arm spider 19 engag-

ing hooks 18 securely fastened to the element 2 shown in Fig. 5. Material is then forced in between the bell and the element 2 and this takes up all of the space 13 to form the part 14 of the coping as shown more clearly in Fig. 4.

In order to be sure that the entire space is filled, small bleed holes 15 are provided which permit the air to be forced out from this space as the material is forced in. After the space has been entirely filled the spider 19 is disengaged from hooks 18 permitting the former plate to be carried downwardly upon a rod, not shown, thus allowing a section of coping to issue from die and mold. The finished product then has the appearance as shown in Fig. 2 in which three pieces of coping, respectively 16, 16, 16 are shown as forming a section of three units. At the points 17 small incisions are provided as the material passes through the die, at which points the three sections 16 may be broken, after firing, into their three component units. It will be seen that a three section unit readily stands up and thus can be easily handled during firing.

From what has been described it is thought the nature of my invention will be readily apparent.

Having however, thus described one form which my invention may take, what I claim as new and desire to secure by Letters Patent is:

A mold for multi-section coping units,

each coping unit having a pair of angularly disposed walls, one of said walls being rather long and the other relatively short, the short wall of one unit angularly approaching the end face of the long wall of another unit, said mold comprising a bell having a triangular exterior, means for rigidly mounting said bell, a surrounding three sided coöperating die element for said bell, the two elements forming an orifice to accommodate three coping units so that the longer wall of one coping unit adjoins and is united to the shorter wall of the other coping unit, and three pairs of V-shaped scoring elements fastened to said bell opposite to the jointure of the coping units so that the three pairs of scoring elements alone form three parts of restricted cross-section whereby when said multi-unit section is withdrawn from said mold, the incisions made by said scoring elements and the acute angled incision due to the adjoining walls provides portions of restricted cross-section to permit separation without waste, said scoring elements of each pair being opposed and making incisions of substantial cross-section.

In witness whereof, I hereunto subscribe my name this 12th day of February, A. D., 1913.

THOMAS HENRY McFERREN.
